E. R. BURTNELL

INTERNAL COMBUSTION ENGINE

Filed May 21, 1925

Fig. 2.

INVENTOR,
EVERETT R. BURTNELL
BY *Martin P. Smith* ATTY.

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed May 21, 1925. Serial No. 31,805.

My invention relates generally to internal combustion engines, and more particularly to a head structure for the adjacent members of a pair of combustion cylinders 5 and the invention herein disclosed is an improvement on a similar invention that forms the subject matter of a co-pending patent application filed by me Feb. 26, 1925, Ser. No. 11,715.

10 The principal objects of my present invention are, to generally improve upon and simplify the construction of the engine cylinder head structure disclosed in my aforesaid pending patent application and further, to 15 provide a common compression and combustion clearance chamber for the two combustion cylinders that is constructed and arranged so that the inducted gases will not be agitated during the scavenging function and 20 mix with the residual gases and products of combustion that are being expelled through the exhaust port.

A further object of my invention is to 25 provide means for igniting the fuel charges, that is compressed in the common compression and combustion clearance chamber, at two separated points, thereby insuring a 30 more uniform and even burning of the compressed fuel charge and consequently enhancing the development of power in the combustion chambers.

With the foregoing and other objects in 35 view, my invention consists in certain novel features of construction and arrangement of parts that will be hereinafter more fully described and claimed and illustrated in the 40 accompanying drawings in which:

Fig. 1 is a vertical section taken lengthwise through the centers of a pair of combustion cylinders and showing my improved head structure applied thereto.

Fig. 2 is a horizontal plane view looking against the underside of my improved head block and which view is taken on 45 the line 2-2 of Fig. 1.

Referring by numerals to the accompanying drawings which illustrate a practical embodiment of my invention, 10 designates a portion of an internal combustion engine 50 cylinder block, in which are formed combustion chambers 11 and 12 that are disposed immediately adjacent to each other and with their axes parallel.

Chamber 11 is provided with charge inlet

ports 13 and chamber 12 is provided with 55 exhaust ports 14.

These inlet and exhaust ports are preferably located in the same horizontal plane, and they are positioned so that they are uncovered and open, only when the pistons that operate within said combustion chambers are at the lower or outer ends of their travel.

Secured to the head end of block 10, is 60 a head block 15, that closes the head ends of chambers 11 and 12 and formed in said head block is a cell or series of cells 16 through which may be circulated a fluid cooling medium.

Formed in the head block 16 and preferably at a point directly above the center of chamber 12 from which leads exhaust port 14, is a substantially spherical chamber 17 and the lower end thereof is connected by a short throat 18, with the upper end of said chamber 12. From its upper end, or the point where it leaves chamber 17, this throat 18 gradually increase in diameter toward its lower end, or the point where it joins the upper end of chamber 12.

Seated in the upper portion of head block 15 and in alignment with the center of chamber 17 and the axis of chamber 12 is an ignition device, such as a spark plug 19 and the inner ends of the electrodes thereof 85 project into the upper portion of said chamber 17.

An elongated throat or chamber 20 leads from the sides of chamber 17 laterally and downwardly through block 15 and the lower 90 end of said throat or chamber communicates directly with the upper or inner end of combustion chamber 11.

The lower end of throat 20 has the same diameter as combustion chamber 11 and said 95 chamber 20 gradually decreases in diameter to the point where it joins chamber 17.

Seated in the side of head 15 is an ignition device such as a spark plug 21 and the inner ends of the electrodes thereof project 100 into throat or chamber 20 directly above the point where the same joins the upper end of chamber 11.

The chamber 17 and throats 18 and 20 constitute a common compression and combustion clearance chamber for combustion chambers 11 and 12, and as the pistons that operate within said chambers 11 and 12

reach the lower or outer ends of their travel, ports 13 and 14 are simultaneously uncovered, thereby admitting a fuel charge volume into chamber 11 through open ports 13. This charge volume passes rapidly upward through chamber 11, throat 20 and chamber 17, and thence downward through throat 18 and chamber 12 and in so doing, this admitted charge volume drives before it, practically all the products of combustion resulting from the previously ignited fuel charge volume, and these residual gases and products of combustion are expelled through exhaust port 14.

15 By virtue of the contour of the common compression and combustion clearance chamber comprising the throats 18 and 20 and chamber 17, the flow of the inducted fuel charge volume through said common 20 chamber will be uniform and steady, devoid of agitation and without tendency to mix with the residual gases that are being expelled.

As the pistons start upward on their succeeding compression stroke, ports 13 and 14 will be closed, and during the remaining portion of the upward or inward travel of the pistons, the admitted charge volume, together with the relatively small amount of 30 residual gases that were left in chamber 12, will be compressed in the common compression and combustion clearance chamber, until, at the point of highest compression, or as the pistons pass high center, said compression charge will be ignited at two separated points by sparks produced between the terminals of the electrodes of spark plugs 19 and 21.

40 This ignition of the compressed fuel charge at two different points in the common clearance chamber, insures a more even and uniform flame propagation through the compressed charge, and the rapid rise in expansion following combustion will be impressed directly upon the heads of the pistons, to drive the same downward on their power stroke.

50 Inasmuch as agitation and dilution of the admitted fuel charge is minimized, the engine may be advantageously operated under my light loads, by reason of the fact that the inducted charge volume will burn efficiently and with successively regularity. This desirable condition is enhanced, owing to the provision of the two ignition devices in the common compression and combustion clearance chamber.

60 The substantially spherical chamber 17, functions as a charge stratification chamber during compression of the admitted fuel charge and the location of one spark plug in this chamber and another in the end of throat 20 that leads from chamber 11 into which the charge volume is admitted, insures ignition of the compressed fuel charge

under all conditions and thereby produces added efficiency in engine operation.

It will be understood that minor changes in the size, form and construction of the various parts of my improved internal combustion engine may be made and substituted for those herein shown and described without departing from the spirit of the invention, the scope of which is set forth in the appended claims.

75

I claim as my invention:

1. In an internal combustion engine, the combination with a pair of combustion chambers, one having inlet port and the other having an exhaust port, of a cylinder head closing the head ends of said combustion chambers, and said head being provided with a common compression and combustion clearance chamber that connects the head ends of said combustion chambers, and which common clearance chamber comprises a substantially spherical chamber that is aligned with the axis of the combustion chamber having the exhaust port, a tapered throat leading from said spherical chamber to the head end of the combustion chamber having the exhaust port, and a laterally disposed curved throat that connects the side of said spherical chamber with the head end of the combustion chamber having the inlet port.

80

85

90

95

2. In an internal combustion engine, the combination with an exhaust port, of a cylinder head closing the head ends of said combustion chambers, and said head being provided with a common compression and combustion clearance chamber that connects the head ends of said combustion chambers, and which common clearance chamber comprises a substantially spherical chamber that is aligned with the axis of the combustion chamber to the head end of the combustion chamber having the exhaust port, a laterally disposed curved throat that connects the side of said spherical chamber with the head end of the combustion chamber having the inlet port, and said head being provided with a cooling fluid circulation cell that practically surrounds said common compression and combustion clearance chamber.

105

110

115

3. In an internal combustion engine, the combination with a pair of combustion chambers, one having inlet port and the other having an exhaust port, of a cylinder head closing the head ends of said combustion chambers and said head being provided with a common compression and combustion clearance chamber that connects the head ends of said combustion chambers and which common clearance chamber comprises a substantially spherical chamber that is aligned with the axis of the combustion chamber having the exhaust port, a tapered throat leading from said spherical chamber to the head end of the combustion chamber having

120

the exhaust port, a laterally disposed curved throat that connects the side of said spherical chamber with the head end of the combustion chamber having the inlet port, an

5 ignition device seated in the head and projecting into the laterally disposed throat adjacent to the point where the same joins

the combustion chamber having the inlet port and an ignition device seated in said head and projecting into said spherical 10 chamber.

In testimony whereof I affix my signature.

EVERETT R. BURTNELL.
